UNITED STATES PATENT OFFICE.

CHARLES F. COLOMB, OF WEST HOBOKEN, NEW JERSEY, ASSIGNOR TO A. WITTNAUER CO., OF NEW YORK, N. Y., A CORPORATION OF NEW YORK.

DESIGN FOR A BRIDGE-PLATE FOR WATCH-MOVEMENTS.

54,981.

Specification for Design.

Patented Apr. 27, 1920.

Application filed October 25, 1919. Serial No. 333,408. Term of patent 14 years.

To all whom it may concern:

Be it known that I, CHARLES F. COLOMB, a citizen of the United States, residing in West Hoboken, in the county of Hudson and State of New Jersey, have invented a new, original, and ornamental Design for a Bridge - Plate for Watch - Movements, of which the following is a specification, reference being had to the accompanying drawing, forming a part thereof.

The figure is a plan view of a bridge plate for watch movements showing my new design.

I claim:—

The ornamental design for a bridge plate for watch movements as shown.

CHARLES F. COLOMB.
